UNITED STATES PATENT OFFICE.

CHARLES EDWARD HASTY, OF ELGIN, ILLINOIS, ASSIGNOR TO HASTY MANUFACTURING COMPANY, OF ELGIN, ILLINOIS, A CORPORATION OF ILLINOIS.

AUTOMATICALLY-OPERABLE VALVE.

1,183,815.

Specification of Letters Patent. Patented May 16, 1916.

Application filed July 1, 1911, Serial No. 636,464. Renewed August 20, 1915. Serial No. 46,529.

To all whom it may concern:

Be it known that I, CHARLES EDWARD HASTY, a citizen of the United States of America, residing at Elgin, in the county 5 of Kane and State of Illinois, have invented a new and useful Automatically-Operable Valve, of which the following is a specification, reference being had to the accompanying drawings, illustrating same.

10 My invention relates to valves of various characters, and to automatically-operable mechanism therefor.

The principal objects of my invention are, to provide an improved valve of the character herein set forth; to provide improved automatically-operable mechanism for such valves; to provide improved means for automatically opening the valve as desired; to provide improved means for holding the 20 valve plug or plunger in set, or closed, position; to provide an improved packing box for such valves; and to provide other improvements hereinafter set forth.

Other objects will be apparent from the 25 following specification.

The spring packing material preferably used in the packing box of this invention is described and claimed in my co-pending application for Letters Patent of the United 30 States, Serial No. 634,599, filed June 21, 1911.

In the accompanying drawings illustrating one form of my invention, Figure 1 is a vertical or longitudinal cross-sectional view 35 of the valve of the invention, with portions shown in elevation, showing the valve in set position; Fig. 2 is a similar view showing the valve in operated position; Fig. 3 is a plan view of one of the packing rings 40 used in the packing box of the invention; and Fig. 4 is a cross-sectional view of the packing ring of Fig. 3, taken on line X—X thereof.

Like characters refer to like parts in the 45 several figures.

In various places where valves are used, such as on airbrake systems of railway cars, it is very desirable to be able to automatically and quickly open a valve at certain 50 times, and to be able to control such operation of the valve from a distance from the valve by some simple and easily-operable means. In railway block-signal systems it is also very desirable in certain instances 55 to have such valve control, operated auto-

matically to control the brakes of the cars. The advantages of such apparatus and such a system are very marked. For instance, with the apparatus of this invention, installed in a suitable system, a motorman on 60 an interurban trolley car cannot run his car into the wrong block without automatically putting on the brake and stopping the car. To procure these advantages, as well as others, the features of this invention are provided.

By reference to the drawings, 1 is the valve casing, having an inlet passage 2 and an outlet passage 3. Within the casing 1 is provided a tapered valve-plug seat 4 70 within which the valve plug 5 fits when the valve is closed, as shown in Fig. 1. The plug 5 has a rod or stem 6 connected therewith and extending out through the valve casing 1 to mechanism controlling the operation 75 of the plug. The valve-operating mechanism comprises a hand wheel 8 attached to the stem 6, a pair of arms 9 9 pivoted at 10 10 between pairs of wings 11 11 on the hand-wheel member 8, links 12 12, pivoted to the 80 respective arms 9 9 at 13 13 and pivoted together at 14, for holding the arms 9 9 against operation, a heat-susceptible or explosive member 15, either an electrical heat-cartridge or a cartridge of gun-cotton or 85 some other explosive, removably held between two terminal members 16 16 which are secured to the links 12 12 respectively, for holding the links 12 12 against operation, and a coil spring 17 surrounding the 90 stem 6 and acting expansively between the operable plug 5 and the stationary packing box 7 to operate the plug 5, wheel 8, arms 9 9, and links 12 12, to the position shown in Fig. 2 when the cartridge 15 gives way 95 or is removed from the members 16 16. Nuts 20 and 21 screwed onto the casing 1 as shown, are for the purpose of holding the arms 9 9 in the position shown in Fig. 1, and for the purpose of forcing these arms 100 9 9 downwardly when screwed up tightly thereagainst, to draw the plug 5 tightly into the seat 4 to tightly close the valve against the pressure of spring 17 and the pressure of the fluid in the inlet passage 2.

The packing box 7 comprises packing rings 18 and 19 between which the spring packing material at 7 is placed, the ring 19 being held in place by a bushing 22 screwed into the end of the casing 1, and the ring 18 be- 110

ing held in place by the coil spring 17 bearing thereagainst. The lower end of spring 17 is held attached to the ring 18, after being screwed into the recess 23 with one convolution of the spring under the outwardly-turned portions 24 24, by the said outwardly-turned portions 24 24. This enables the ring 18 to be removed with the spring 17 from the top of the valve casing, 5 when the nuts 25 are removed from the stem 6. When the plug 5 is operated to the position shown in Fig. 2, the spring 17 in expanding reduces the pressure on the spring packing material 7 and thereby permits the 10 latter to loosen its hold on the stem 6 to allow the mechanism to operate freely to the 15 position shown in Fig. 2.

The cartridge 15 may be heated by an electric current in the circuit 26, if an electrical 20 cartridge, or exploded by a spark therein from the circuit 26, if of gun-cotton, or removed from the members 16 16 by some suitable means, to permit the operation of the apparatus from the position shown in 25 Fig. 1 to the position shown in Fig. 2. When it is desired to reset the apparatus for another operation, it is only necessary to place a new or repaired cartridge between the members 16 16 as shown in Fig. 1, after 30 first drawing the parts to the position shown in Fig. 1 against the tension of spring 17, and then screwing the nuts 21 and 20 down tightly against the ends of the arms 9 9 to tightly draw the plug 5 into the seat 4. 35 In operating the valve, the fluid pressure (which in some instances may be a good many pounds to the square inch) in the inlet passage 2 presses against the underneath side of the plug 5 and helps the spring 17 to operate the mechanism. In case the spring 17 should become disabled, the fluid pressure 40 may operate the valve by itself. It will be readily seen that when the mechanism is in the position shown in Fig. 2, the valve passage 45 is open.

The wheel member 8 has a hollow cylindrical portion 27 thereon, attached to the wings 11 11 and adapted to move over the lower end of the valve casing 1 when the 50 valve is operated from one position to another.

The portions 5, 6, 8, 9, 9, 12, 12, 15, as a whole, may be turned around relatively to the valve casing 1 if desired, to cause the 55 plug 5 to fit more snugly into the seat 4 in case the fit is better in one position than in another.

For the spring 17 I preferably use piano wire, copper plated to prevent rusting.

60 Of course the packing box herein set forth may be used on other devices besides valves.

I do not wish to limit this invention to all 65 of the particular details herein set forth, as various modifications thereof may be made

and utilized without departing from the scope of the appended claims.

What I claim as my invention is:

1. A valve of the character set forth having a casing with a valve-plug seat therein, a plug for the seat, said plug having a stem extending out through the wall of the casing, a packing box within the casing around the stem, a coil spring surrounding the stem and acting between the packing box and the plug, said spring tending to unseat the plug, a hand wheel member attached to the end of the stem, a pair of arms pivoted to the hand-wheel member, a pair of links for holding the said arms against operation on their pivots, a heat-cartridge normally holding the said links from operating but permitting them to operate upon abnormal heating, and an annular member threaded onto the valve casing for forcing the plug into its seat through the agency of the said arms and for holding the plug in its seat, the giving-away of the heat-cartridge permitting the said links, arms, stem and plug to operate whereby the plug is unseated and the valve passage opened. 70 75 80 85 90

2. A valve of the character set forth having a casing with a valve-plug seat therein, a plug for the seat having a stem projecting from the casing, a packing box for the stem, a coil spring surrounding the stem, acting between the packing box and the plug and tending to unseat the plug, a pair of arms for normally holding the plug against operation, a pair of links for holding the said arms against operation, a heat-cartridge controlling the operation of the said links, and an annular member threaded onto the valve casing and adapted to be tightened up against the ends of the said arms to hold the plug tightly in its seat, the giving-away of the heat-cartridge permitting the operation of the apparatus whereby the plug is unseated and the valve passage opened. 95 100 105 110

3. A valve of the character set forth having a casing provided with a plug seat, a plug for the seat having a stem projecting from the casing, a coil spring surrounding the stem, acting on the plug and tending to unseat same, an adjustable ring on the casing, a pair of arms bearing against the said ring and normally holding the plug from operating, a pair of links for holding the said arms from operating, and a heat-cartridge controlling the operation of the said links and permitting them to operate under abnormal conditions whereby they cause the disengagement of the said arms from the said ring and thereby permit the said spring to unseat the plug. 115 120 125

4. A valve of the character set forth having a plug seat and a valve plug therefor, spring mechanism acting on the plug and tending to unseat it, a pair of arms co-operating with the valve plug, an adjustable ring 130

coöperating with the said arms to normally hold the plug in its seat, and a heat-susceptible link controlling the operation of the said arms and permitting of their operation under abnormal heating to allow the spring mechanism to unseat the plug.

5. The combination in a valve, of a casing, a valve plug, a seat for the plug, spring mechanism for raising the plug from its seat to open the valve, a pair of arms coöperating with the valve plug, a thermally-controlled link for controlling the operation of the said arms, and an adjustable nut carried by the valve casing and adapted to be screwed against the ends of the said arms when in normal position to force and normally maintain the plug tightly in its seat.

6. The combination in a valve, of a casing, a valve plug, a seat for the plug, spring mechanism for raising the plug from its seat to open the valve, a pair of arms coöperating with the valve plug, an electrothermally-controlled link for controlling the operation of the said arms, and an adjustable nut carried by the valve casing and adapted to be screwed against the ends of the said arms when in normal position to force and normally maintain the plug tightly in its seat.

30 7. The combination in a valve, of a casing, a valve-plug member, means for nor-

mally maintaining the plug in a predetermined position comprising a pair of thermally-controlled arms pivoted to the valve-plug member and straddling a portion of the 35 valve casing, and adjustable mechanism carried by the valve casing and adapted to be adjusted tightly against the ends of the said arms.

8. The combination in a valve, of a casing, a valve plug member, means for normally maintaining the plug in a predetermined position comprising a pair of thermally-controlled arms attached to the valve plug member, and a pair of lock-nuts 45 carried by the valve casing and adapted to be adjusted tightly against the said arms.

9. The combination in a valve, of a casing, a valve-plug member, means for normally maintaining the plug in a predetermined position comprising a pair of arms pivoted to the valve-plug member and straddling a portion of the valve casing, and adjustable mechanism carried by the valve 50 casing and coöperating with the said arms. 55

As inventor of the foregoing I hereunto subscribe my name, this 23rd day of June, 1911.

CHARLES EDWARD HASTY.
